Remover #T-3179.

Primary Examiner—Bruce W. Dunkins
Assistant Examiner—Clare E. Heflin

[57] CLAIM

The ornamental design for the slate shingle remover, as
shown and described.

DESCRIPTION

FIG. 1 is a top perspective view of the slate shingle
remover showing my new design;

FIG. 2 is a side elevational view thereof, the opposite
side being a mirror image;

FIG. 3 is a front elevational view thereof;

FIG. 4 is a rear elevational view thereof;

FIG. 5 is a bottom plan view thereof.
